FURNITURE SPRING SEAT

Charles C. Meutsch, Buffalo, N. Y.

Application June 14, 1932, Serial No. 617,144

4 Claims. (Cl. 155—179C)

This invention relates to a cushion or spring suspension for chairs, davenports and the like and more particularly to a spring suspension having a vertically movable, resilient frame arranged within and resiliently connected to the main frame of the chair (or other article of furniture).

The principal object of the invention is to provide a spring suspension in which resilience is obtained by the use of a plurality of metal springs, a number of sets of which act in series with each other, so as to enable one set of springs to softly oppose very light external loadings, and at the same time to back this "soft" set of springs by a second and a third set of springs (both of the helical and elastic bar types) whereby intermediate and heavy loads are also resiliently supported without possibility of "striking bottom".

Another object of the invention is to obtain such a resilient movement in a smooth and noiseless manner. A still further object of the invention is to provide an improved and simple means of securing the hour-glass shaped "cushion" springs to the sub or movable frame. Numerous other objects of the invention and practical solutions thereof are disclosed in detail in the herein patent specification wherein:

In the accompanying drawings:

Fig. 1 is a horizontal section of a chair with its spacing or centralizing cords, padding, etc. removed to expose the improved spring suspension which is arranged immediately below within the main frame of said chair.

Fig. 2 is a vertical section thereof taken on line 2—2, Fig. 1.

Fig. 3 is an enlarged, vertical, fragmentary section through one side of the chair taken on line 3—3, Fig. 1.

Fig. 4 is an enlarged perspective of one of the sheet metal hangers thereof.

Fig. 5 is an enlarged perspective of one of the sheet metal clips thereof prior to being bent over the lower turn of its companion spring.

Fig. 6 is an enlarged perspective of a modified form of hanger.

Fig. 7 is an enlarged, fragmentary, top plan of a modified movable frame bar.

Fig. 8 is a vertical, transverse section thereof taken on line 8—8, Fig. 7.

Fig. 9 is a fragmentary, horizontal section through a chair provided with a modified form of spring suspension.

Fig. 10 is a fragmentary, vertical section through a chair provided with another modified form of spring suspension.

Fig. 11 is an enlarged perspective of the type of sheet metal hanger used in Fig. 10.

Similar characters of reference indicate like parts in the several figures of the drawings.

My invention may be embodied in various forms and in furniture spring suspensions of various constructions, and the present applications are therefore to be regarded merely as some of the possible organizations which come within the scope of my invention and satisfactorily carry out the function of same in practice. As here shown, and referring for the present to only Figs. 1—5, the same is constructed as follows:

It will be assumed, for purposes of illustration, that the invention is to be applied to an ordinary stiff backed four legged chair. The main frame A of such a chair comprises the vertical rear legs 20, 20 joined together by the horizontal, transverse, rear, frame beam 21;—the vertical, front legs 22, 22 joined together by the horizontal, transverse, front, frame beam 23;—and the horizontal, longitudinal, side, frame beams 24, 24 which connect the front and rear sets of legs.

Arranged at suitable intervals on the inside of the beams 21, 23 and 24, 24 are a plurality of sheet metal hangers B. Each of said hangers comprises an upper, horizontal, securing flange 25 which lies upon the upper face of a companion frame beam and is secured thereto by a nail 26 or otherwise. The inner portion of each hanger is bent sharply downward to form a main, vertical, hanger body 27 which is secured to the inner, vertical surface of its companion frame beam by four nails 28.

Formed integrally with the upper portion of said main body 27 of each hanger B is a vertical hook 30, the rear portion of which projects inwardly at an angle to the main body 27 and terminates in a flat, vertical portion which is parallel to said main body 27. The upper, outer end of said hook 30 is bevelled at 31 and said hook is further provided with a notch 32 located inwardly of said bevel 31. Adapted to engage with said notch 32 is a depending, vertical, helical, overload spring 33, the upper eye of which is conveniently slid into place upon said bevel 31 with said spring under tension, this being its condition while being assembled and after assembly.

The lower end of each hanger B is bent sharply and horizontally inward to form a pressure flange 34 which is medially cut out at 35. The shape of this cut out portion 35 is illustrated as rectangular, but it will be obvious to those skilled in the art that this question is merely one of die cost and die maintenance, and that said opening may

be of round or any other suitable shape. The aforescribed overload spring 33 is received within said opening 35 and has its lower curled end or eye received within a spring aperture 36 punched or otherwise formed adjacent the outer end of a resilient, movable-frame bar 37. The tension of the overload spring 33 causes said bar 37 to be resiliently urged upwardly toward the lower, flat, horizontal surface of the pressure flange 34.

The upper surface of each bar 37 is covered with a strip of felt or other sound-absorbing material 38, the same having a pair of spring apertures 40 at its opposite ends registering with the spring apertures 36 at the opposite ends of its companion bar 37. This strip of sound-absorbing material 38 has substantially the same form as that of the companion bar 37 which it overlies, but preferably extends a short distance beyond the ends of said bar (see Fig. 3) so as to absolutely prevent any metallic contact between the bar 37 or the springs 33 and their companion pressure flanges 34. Lateral displacement of each of said bars 37 is prevented by the provision of a pair of lateral guides 41 which are formed integrally with each sheet iron hanger B and are bent vertically downward at the extreme outer edge of the pressure flange 34 thereof.

Within the main frame A of the chair are arranged two sets of bars 37 which are arranged in the form of rectangular lattice work, i. e., having the one set arranged at right angles and below the other set. These two sets of bars 37, together with their apertures, constitute a sub-movable frame C. At each intersection of and resting upon said bars 37 is a cushion spring 42 of the conventional helical, hour-glass-shape type.

Each cushion spring 42 at its lower end is secured by a pair of clips D at two diametrically opposite points to the underneath one of the companion, crossed bars 37. Each of said clips D (see Fig. 5) is constructed of sheet metal and has a main body portion 43 which is adapted to lie flat against the lower face of said underneath bar 37. Each clip is constructed of a substantially rectangular piece of sheet iron stock which is slit along the lines 44, the corner portions being then turned back to form tongues 45 which, in the assembling operation, are curled around the lower turn of their companion cushion spring 42 in the manner indicated by the dotted and full lines of Fig. 5. Each pair of clips holds down firmly the opposite sides of the lower turn of their companion cushion spring 42, while the intermediate portion of said lower turn of said cushion spring is pressed upwardly by the upper one of the companion pair of crossed bars 37 (see Fig. 2). By this construction the lower turn of said cushion spring is held under tension, so that its connection with the movable frame C is rendered free from objectionable vibration noises, such noises being additionally prevented by the interposition of the sound deadening strips 38 between said cushion spring and its companion pair of metallic crossed bars 37.

The upper ends of the cushion springs are connected (see Fig. 2) by a plurality of centralizing cords 45 in the usual and well known manner, the whole being overlaid by the usual pad and cover (not shown).

The three front cushion springs 42a are arranged somewhat differently from the other cushion springs 42, but this construction is old and does not affect the present invention and

hence need not be further described, except to note in passing that said front springs 42a are mounted directly on the main frame A and are entirely independent of the movable frame C.

All of the bars 37 are constructed of resilient material, the resilience or "softness" of which is increased by curving each bar at each end at 46 and 47. When a child is sitting upon the chair or if otherwise the load upon any one or more of the cushion springs 42 is relatively small in amount, said cushion springs will yieldingly flex to provide a soft and comfortable spring suspension for such a light load. In such a case substantially no flexure of the movable frame C occurs and no flexure whatever of any of the 15 overload springs 33.

If the localized pressure upon any one or more of the cushion springs 42 be increased beyond the amount just indicated, the force exerted by said cushion springs 42 will finally become great enough to flex the bars 37 to a greater or less degree, but without, under these conditions, causing any flexure of the overload springs 33.

If now the load be increased still more, as for instance by a two hundred pound man suddenly dropping his full weight upon the chair, then, not only will the cushion springs 42 and the bars 37 be more greatly flexed, but a load will have been imposed upon one or more of the overload springs 33 greater than their normal or unflexed load, thereby causing one or more of said overload springs to be stretched beyond the position shown in the drawings and the ends of their companion bars to be depressed.

If the load upon each portion of the spring 33 suspension is sufficiently great then the entire movable frame C is caused to be depressed. During this downward movement of said frame C the ends of the bars 37 are laterally guided by the lateral guides 41. If now this very heavy load 40 be released, the various resilient members (cushion springs 42, resilient bars 37 and overload springs 33) will return to their normal positions as illustrated in the drawings. In this return to normal position there is no noisy contacting of metallic parts. For instance if the imposed load is suddenly released, the sudden returning upward of the ends of the bars 37 against the lower face of the pressure flange 34 is rendered noiseless by the sound absorbing material 38. 50

In Fig. 6 is shown a modified form of overload spring hanger. In this case the lateral guides 41 of Figs. 1-4 are dispensed with, the same being substituted by the upturned lateral guides 41a which bear against the lower sides of their companion overload spring 33, the bar 37 being thus indirectly guided laterally by the guiding of said overload spring 33 whose lower end is connected with said bar 37. 55

Figs. 7 and 8 illustrate a modified and rigid form of bar 37b of special curvilinear cross section, the central portion being provided with a single longitudinal corrugation 48 to provide bending strength, and each of the outer longitudinal edges being provided with a single, symmetrical, reverse corrugation 49 and flange 50 which provides additional bending strength and also permits said flange 50 to be bent sharply inward at 51 so as to lap over the lower turn of a specially formed cushion spring 42b. Said 70 lower turn of said cushion spring 42b is preferably, as shown, of elliptical form in plan view and has its medial, longitudinal portions bent in a curve 52 to conform to the medial corrugation 48 of said bar 37b. At 53 the flange 50 is not 75

only bent over aforesaid lower turn of the cushion spring 42b but is curled partially around said lower turn, thereby preventing longitudinal displacement of said cushion spring.

- 5 In Fig. 9 is shown a further modification of the invention. In this case the resilient bars 37c are formed similarly to the bars 37 of Figs. 1-5, but are not arranged to cross each other, each cushion spring 42 being secured to a pair 10 of parallel bars 37c by a pair of clips Dc each of which is similar to the clip D of Figs. 5, 1 and 2. In this case a double form of hanger Bd is employed, each of said hangers supporting a companion pair of overload springs 33 and a 15 companion pair of bars 37c.

In Figs. 10 and 11 is shown a form of the invention in which no cushion springs at all are used. In this case each resilient bar 37d is given a small bend at 46d and a large radius bend 47d, 20 the latter causing the central part of the bar to be elevated well up above the top of the main frame A. A number of such bars 37d are preferably (though not necessarily) arranged at right angles to each other and secured together by 25 countersunk rivets 53. To have the upper surface of the spring suspension conform more closely with the shape of the main frame A of the furniture, flexible ribs 54 are secured to the bars 37d, preferably by the same rivets 53 which secure said 30 bars together. Such a spring suspension requires that each of said bars 37d be not only laterally but also longitudinally guided. This is effected by the provision of a rubbing plate 55 (see Fig. 11) formed integrally with and extending down 35 from the main body of the hanger Bd. This rubbing plate rests against and hence is backed by the vertical, inner face of the frame A. Thus, when its companion bar 37d shifts longitudinally, the end of said bar comes into contact with said 40 rubbing plate 55 backed by the main frame A and

any further longitudinal movement is prevented. Such a rubbing plate can be used in any of the other spring suspensions shown in the drawings, but is of no particular value in such cases as the imposed longitudinal forces are there taken 5 care of by the centralizing cords 45, which obviously are not employed in the construction of Figs. 10 and 11, though obviously this may be done if desired.

I claim as my invention:

1. A furniture spring seat comprising: a main frame; a pressure flange secured to said frame; a bar adapted to support a person's weight; a pair of lateral guides connected with said flange and embracing opposite edges of said bar; and 15 an overload spring resiliently urging said bar toward said flange.

2. A furniture spring seat comprising: a main frame; a hanger secured to said main frame and having an opening; an upper, horizontal, securing flange, a lower horizontal pressure flange, and a hook; a bar disposed below said pressure flange; and an overload spring secured at its upper end to said hook and, at its lower end, passing through said opening and secured to said bar. 25

3. A furniture spring seat comprising: a main frame; a hanger having a pressure flange and a hook which is bevelled at its outer end; a bar disposed below said pressure flange; and a spring secured to said bar and to said hook inwardly of 30 the bevelled end thereof.

4. A furniture spring seat comprising: a main frame; a hanger having a pressure flange and a hook which is bevelled at its outer end and is provided with a notch located inwardly of said 35 bevelled end; a bar disposed below said pressure flange; and a spring secured to said bar at one end and engaging at its other end with said notch.

CHARLES C. MEUTSCH. 40
